LIQUID CONGEALING APPARATUS

Jules N. Saler, Springfield, Mass., assignor to
Westinghouse Electric & Manufacturing Com-
pany, East Pittsburgh, Pa., a corporation of
Pennsylvania

Application October 16, 1935, Serial No. 45,246

8 Claims. (Cl. 62—108.5)

My invention relates to liquid congealing apparatus and particularly to a grid structure for forming ice cells suitable for table use.

It is an object of my invention to provide an improved flexible grid structure for congealing liquids for table use.

It is another object of my invention to provide improved liquid congealing apparatus from which congealed liquid is readily removable.

These and other objects are effected by my invention, as will be apparent from the following description and claims taken in connection with the accompanying drawing, forming a part of this application, in which:

15 Fig. 1 is a top view of my improved liquid congealing apparatus and shows my improved grid structure disposed in a liquid containing pan;

Fig. 2 is a side elevational view of the liquid congealing apparatus; and,

20 Fig. 3 is a perspective view of the grid structure.

Referring specifically to the drawing for a detailed description of my invention, numeral 11 designates a liquid containing pan in which a grid structure, generally designated at 12, is disposed.

25 The grid structure 12, preferably formed of stainless steel, embodies a longitudinal wall 13 and a series of spaced transverse walls 14 extending from opposite sides of the longitudinal wall 13 to form, with the pan 11, four corner cells 15 and a series of intermediate cells 16 disposed in rows between the corner cells. The cells 15 and 16 provide cubes of a size suitable for table use.

30 The longitudinal wall 13 is formed of two sheets of flexible metal 17 and 18, which are fastened by clips 19 at the extremities thereof, and are

35 preferably, though not necessarily, fastened by any suitable means, such as welding at 21, to prevent spreading of the sheets 17 and 18. The transverse walls 14 are formed by bending the sheets 17 and 18 at right angles, then doubling the sheets at 22 back to the plane of the longitudinal wall 13, then again bending the sheets at right angles to form the next section of the

40 longitudinal wall. The transverse walls 14, are therefore, formed of two contiguous sheets of metal 23 and 24, doubled at 22.

45 As is apparent from the drawing, the transverse walls 14 on opposite sides of the longitudinal wall 13 are staggered with respect to each other. By staggering the transverse walls 14, greater flexibility of the grid structure 12 is obtained, thus facilitating removal of the frozen liquid from the grid structure 12.

50 Handles 25 are pivotally fastened to the ex-

tremities of the longitudinal wall 13 and, when rotated outwardly, bear on the pan member 11 to raise the grid 12 and break the ice bond between the congealed liquid and the pan 11 so that the grid structure 12 with the frozen liquid 5 therein is readily removed from the pan. The handles 25 are then used to impart flexing movement to the grid to facilitate removal of the frozen liquid therefrom. Such a construction is fully described and claimed in my copending application, Serial No. 17,220, filed April 19, 1935 for Liquid congealing apparatus, and assigned to the assignee of the present invention.

The transverse walls are also preferably fastened together, such as by welding at 26 adjacent 15 the bottom of each transverse wall member, to impart stiffness to the grid structure 12 in a direction upwardly of the pan 11, while not affecting the flexibility of the grid structure 12 in the remaining directions. When the handles 25 20 are rotated, the grid structure 12 is, therefore, raised an equal distance along its entire length so that the bond between the congealed liquid and the pan is readily broken. The stiffening of 25 the flexible grid structure by fastening the transverse double walls adjacent the bottom thereof is fully described and claimed in my copending application, Serial No. 710,611, filed February 10, 1934, for Ice freezing device and assigned to the assignee of the present application.

30 From the foregoing it will be apparent that I have provided improved ice congealing apparatus from which congealed liquid is readily removed, and have also provided an improved flexible metal grid structure from which congealed liquid is 35 readily obtainable.

While I have shown my invention in but one form, it will be obvious to those skilled in the art that it is not so limited, but is susceptible of various changes and modifications without departing 40 from the spirit thereof, and I desire, therefore, that only such limitations shall be placed thereupon as are imposed by the prior art or as are specifically set forth in the appended claims.

45 What I claim is:

1. A receptacle for producing frozen ice cells comprising a pan and a flexible grid structure therefor dividing said pan into four corner cells and a series of intermediate cells disposed in rows and extending between the corner cells, said grid structure embodying a longitudinal wall and a plurality of spaced walls extending transversely from opposite sides of the longitudinal wall and being formed of two sheets of metal disposed contiguous to each other and capable of 50 55

relative movement therebetween, the transverse walls on one side of the longitudinal wall being staggered with respect to the transverse walls on the other side of the longitudinal wall.

5. 2. A receptacle for producing frozen ice cells comprising a pan and a flexible grid structure therefor dividing said pan into four corner cells and a plurality of intermediate cells disposed in rows and extending between the corner cells, said grid structure embodying a longitudinal wall formed of two sheets of metal disposed contiguous to each other and also embodying a plurality of spaced walls extending transversely from opposite sides of the longitudinal wall and being 10 formed of two sheets of metal disposed contiguous to each other and capable of relative movement therebetween, the transverse walls on one side of the longitudinal wall being staggered with respect to the transverse walls on the other 15 side of the longitudinal wall.

3. A receptacle for producing frozen ice cells comprising a pan and a flexible grid structure therefor dividing the pan into four corner cells and a series of intermediate cells disposed in rows and extending between the corner cells, said grid structure embodying a longitudinal wall formed of two sheets of metal disposed contiguous to each other and fastened together and also embodying a series of spaced walls extending 20 transversely from opposite sides of said longitudinal wall, the transverse walls on one side of the longitudinal wall being staggered with respect to the transverse walls on the other side of the longitudinal wall.

35. 4. A receptacle for producing frozen ice cells comprising a pan and a flexible grid structure therefor dividing said pan into four corner cells and a series of intermediate cells disposed in rows and extending between said corner cells, said grid structure embodying a longitudinal wall formed of two sheets of metal and also embodying a plurality of spaced walls extending transversely from opposite sides of said longitudinal wall and formed of two sheets of metal fastened together 40 near the bottom thereof to prevent substantial flexing of the grid structure in a direction upwardly of the pan, said transverse walls on one side of the longitudinal wall being staggered with respect to the transverse walls on the other side 45 of the longitudinal wall.

5. A receptacle for producing frozen ice cells comprising a pan and a flexible grid structure therefor dividing said pan into four corner cells and a series of intermediate cells disposed in rows and extending between said corner cells, said grid structure embodying a longitudinal wall and a plurality of spaced walls extending transversely from opposite sides of said longitudinal wall, the transverse walls on one side of the longitudinal wall being staggered with respect to the transverse walls on the other side of the longitudinal wall, and means disposed on the grid structure for breaking the ice bond between the ice cells and the pan to facilitate removal of the grid structure from the pan and for thereafter imparting flexing movement to the grid structure to facilitate removal of the ice cell therefrom.

6. A receptacle for producing frozen ice cells

comprising a pan and a flexible grid structure therefor dividing said pan into four corner cells and a series of intermediate cells disposed in rows and extending between said corner cells, said grid structure embodying a vertically disposed longitudinal wall formed of two sheets of metal and also embodying a plurality of vertically disposed spaced walls extending transversely from one sheet of said longitudinal wall and formed of two sheets of metal, a plurality of vertically disposed spaced walls disposed intermediate of the first spaced walls and extending transversely from the other sheet of said longitudinal wall and formed of two sheets of metal, and means for fastening said sheets of the longitudinal walls together, said fastening means being disposed on the longitudinal wall between an intermediate spaced transverse wall and only one of the opposite transverse walls on the other side of the longitudinal wall to afford separation 20 of the two sheets of each of said transverse walls.

7. A receptacle for producing frozen ice cells comprising a pan and a flexible grid structure therefor dividing said pan into four corner cells and a series of intermediate cells disposed in rows and extending between said corner cells, said grid structure embodying a vertically disposed longitudinal wall formed of two sheets of metal and also embodying a plurality of vertically disposed spaced walls extending transversely 30 from one sheet of said longitudinal wall and formed of two sheets of metal, a plurality of vertically disposed spaced walls disposed intermediate of the first spaced walls and extending transversely from the other sheet of said longitudinal wall and formed of two sheets of metal, and means for fastening said sheets of the longitudinal walls together, said fastening means being disposed between the transverse walls on one side of said longitudinal wall and at least 40 some of said intermediate transverse walls on the other side of the longitudinal wall.

8. A receptacle for producing frozen ice cells comprising a pan and a flexible grid structure therefor dividing said pan into four corner cells 45 and a series of intermediate cells disposed in rows and extending between said corner cells, said grid structure embodying a vertically disposed longitudinal wall formed of two sheets of metal and also embodying a plurality of vertically disposed spaced walls extending transversely from one sheet of said longitudinal wall and formed of two sheets of metal, a plurality of vertically disposed spaced walls disposed intermediate of the first spaced walls and extending 55 transversely from the other sheet of said longitudinal wall and formed of two sheets of metal, means for fastening said sheets of the longitudinal walls together, said fastening means being disposed on the longitudinal wall between 60 an intermediate spaced transverse wall and only one of the opposite transverse walls on the other side of the longitudinal wall to afford separation of the two sheets of each of said transverse walls, and means for fastening the sheets of said transversely extending walls near the bottom thereof to prevent substantial flexing of the grid structure in a direction upwardly of the pan.

JULES N. SALER.
